INVENTOR.
LeRoy G. Clark

BY *Thomas Donnelly*
ATTORNEY.

UNITED STATES PATENT OFFICE.

LE ROY G. CLARK, OF WAYNE COUNTY, MICHIGAN.

SIGN.

Application filed November 20, 1923. Serial No. 675,839.

My invention relates to a new and useful improvement in a door sign and has for its object the provision of a door sign which will be simple in structure, economical of manufacture and highly efficient in use.

Another object of the invention is the provision of a door sign, having illuminating means associated therewith and operable through a door bell energizing means.

10 Another object of the invention is the provision of a door sign, having a door bell operating means attached thereto, and electrically connected with illuminating means for the door sign.

15 Another object of the invention is the provision of a door sign, having illuminating means associated therewith, said illuminating means being mounted in a casing so constructed as to afford ready and easy access 20 to said illuminating means.

Other objects will appear hereinafter.

The invention consists in the combination and arrangements of parts hereinafter described and claimed.

25 The invention will be best understood by reference to the accompanying drawings which form a part of this specification, and in which,

Fig. 1 is a front elevational view of the 30 invention,

Fig. 2 is a transverse sectional view of the invention,

Fig. 3 is a sectional view taken substantially on line 3—3 of Fig. 2, and,

35 Fig. 4 is a diagrammatic view showing the wiring used in the invention.

The invention is adapted primarily for use with door signs and has associated with it, and operating in connection therewith, a 40 door bell of the conventional type, operable upon the closing of a switch through the means of a button which is normally spring-held in inoperative position.

The invention in its preferred form comprises a casing having a back 9 provided with a peripheral flange 10 having a bead 11 extending around the flange. The casing is adapted for mounting to a wall or the like by suitable fastening means, such as screws, 45 nails or the like. The flange 10 is cut away at the base thereof, as at 12. The back is made preferably of a stamping from a single piece of metal and is provided at its base with an integral extension 13 on which is 50 mounted a door bell casing 14 having the

usual push button 15 which is operated to close a circuit leading to an electrically operated bell 32. The casing is provided with a top 17 which comprises a flange formed on the front wall 19, said flange being formed 60 integral with the front wall 19. The front wall 19 is cut away in the center thereof to provide a frame for framing the glass 22 or other transparent or translucent closure which is positioned within the frame. A 65 bead 18 is formed at the line of juncture between the flange 17 and the front wall 19. Metal strips 20 are mounted on the frame at the inner side thereof and are adapted to be folded upon the closure 22, these strips 70 20 serving to hold the closure firmly in position and being of a pliable material so that they may be folded into operative position or into inoperative position to allow of the quick and easy removal or replacement of 75 the closure in the frame. The flange 17 extends around the frame and the base 21 thereof is shorter than the top so that the housing or casing converges toward the base. Mounted on the inner side of the flange 10 80 is a leaf spring 23 provided with a stud 24 adapted for projection through openings formed in the flange 10 and the flange 17 so as to lock these parts in fixed relation to each other when these openings are brought into 85 registration. A knuckle 16 is formed in the portion 13, from a tongue punched therefrom, and cooperating knuckles 16' are formed from the flange 21, a suitable pintle being projected through these knuckles for 90 holding the back and the remaining portion of the casing in swingable relation.

A cable 25 conducts electrically energized wires to the bell switch and a cable 29 serves to conduct a wire to the light bulb 28, which 95 is mounted in a suitable socket 26 supported by a bracket 27, so constructed as to project the light well into the casing, at the center thereof, the bracket being mounted in any suitable manner to the flange 10, preferably 100 at the top thereof.

The wiring used in the operation of an electric door bell is generally run through a transformer, where a battery is not used, and in the drawings I have shown the use of the 105 door bell with a transformer, although it is apparent that my invention can be used equally well where a battery is used. The wires 33 and 34 lead into the transformer and the wire 33' is connected to one of the 110

contacts of the door bell switch 15. The wire 34' is connected to the coils which operate the door bell 32. The wire 33" is connected to the other contact of the door bell 5 switch 15 and to the coils which operate the door bell. Upon closing the circuit through pressing the push button the coils are energized and the bell is operated.

The wire 33' is connected to the light bulb 10 28. The wire 34''' is grounded as at 34" and is connected to one of the contacts of the switch 35 which is connected by the wire 35' to the light bulb 28. The arrangement is such that the light 28 in the casing may be 15 lighted upon the closing of the switch 35, which is usually mounted within the house at some convenient place. In this way I have utilized the wires which serve to operate the door bell for illuminating the casing 20 by means of the light 28.

Mounted on the closure of the casing are indicating means which may be chosen at will, depending upon what the casing is used for, as will be readily understood. In the 25 drawings I have shown numbers mounted on the closure so that the casing may be used for indicating the house number to which it is attached. These indicating means are glued to the surface of the closure exteriorly of the 30 casing, the surface thereof being varnished or otherwise suitably treated to protect the same against the elements.

By constructing the casing in the manner shown the interior of the casing is accessible 35 for cleaning the bulb or for changing it or making repairs. By cutting away the flange 10 at the base thereof, the wires passing into the interior of the casing pass through the flange 21 alone, so that in opening or closing the casing there will be a minimum amount of wear on these wires.

With signs such as described herein, and particularly when the same are used for 40 house members, the casing is usually mounted a considerable distance above the street, so that if the closure bearing the numbers were perpendicular the numbers thereon would not be legible from the street level. By 45 forming the casing with the top wider than the bottom and having the closure on which the numbers appear, inclined downwardly toward the rear of the casing the numbers 50 become more directly visible from the street 55 level.

The bulb used in the casing may be one of small amperage so that if desired the occupant of the house may have the switch 35 closed during the entire night, thus leaving 60 the door number illuminated at all times during the night, with very little expense.

While I have illustrated and described the preferred form of structure I do not wish to limit myself to the precise details of structure shown, but desire to avail myself of such

variations and modifications as come within the scope of the appended claims.

Haying thus described my invention, what I claim as new and desire to secure by Letters Patent is:

1. A door sign comprising a casing having a rear wall; a flange projecting forwardly from said rear wall and cut away at the base thereof, side, bottom and top walls overlapping said flange and being hingedly connected to said rear wall at said cut away portion; a flange projecting inwardly of said side walls adapted to provide a frame; a closure for said frame; means for retaining said closure in said frame; and yieldable 75 means for locking said side walls in said overlapping position.

2. A door sign comprising a casing having a rear wall; a flange projecting forwardly thereof and cut away at its base portion; side, bottom and top walls overlapping said flange and hingedly connected to said rear wall at its cut away portion; a flange projecting inwardly from said side walls to provide a frame; a closure adapted for 80 mounting in said frame; an illuminating means mounted in said casing; a projection on said rear wall projecting downwardly therefrom below said cut away portion to provide a carrying means for a switch used therewith; a leaf spring mounted at one end on the under surface of said rear wall flange; a stud projecting upwardly from the loose end of said spring adapted for projecting through an opening in said rear wall flange and in a registered opening in said wall for locking said side wall in said overlapping position, said cut away portion providing a space for the projection of wires into said casing for connection with said illuminating means.

3. A door sign comprising: a casing having a rear wall; a flange projecting forwardly of and extending around said rear wall and cut away as the base of said rear wall centrally thereof; an integral depending portion on said rear wall at said cut away portion for providing a switch support; a front for said casing comprising: side walls, a top wall, a bottom wall and a front wall, said top, bottom and side walls overlapping said flange; means for hingedly connecting said front at its bottom wall to said rear wall at said cut away portion, said bottom wall being of less height than said top wall and said front wall being extended angularly to said rear wall converging relatively thereto at its bottom side, said front wall being cut away within its marginal edges to provide a frame; a transparent closure for said frame; means for retaining said closure in position in said frame; illuminating means mounted in said casing; a wire connected to said illuminating means and projected through said bottom wall at said cut away 120 125 130

portion and means for locking said front against swinging movement relatively to said rear wall.

4. In a sign; a casing having a rear wall; 5 a flange mounted thereon projecting forwardly thereof and having a portion at the base of said rear wall cut away; a front for said casing having a wall forming portion for overlapping said flange; means for

swingably connecting said front on said rear wall at said cut away portion; illuminating means mounted in said casing and wiring connected with said illuminating means and extending exteriorly of said casing at said cut away portion. 10 15

In testimony whereof I have signed the foregoing specification.

LE ROY G. CLARK.
